UNITED STATES PATENT OFFICE.

WALTER M. RAND, OF OLNEY, ILLINOIS.

FEED MECHANISM FOR ROLLER-MILLS, &c.

SPECIFICATION forming part of Letters Patent No. 339,468, dated April 6, 1886.

Application filed July 7, 1885. Serial No. 170,859. (No model.)

To all whom it may concern:

Be it known that I, WALTER M. RAND, a citizen of the United States, residing at Olney, in the county of Richland and State of Illinois, have invented certain new and useful Improvements in Feed Mechanism for Roller-Mills and other Machines, of which the following is a specification.

In roller-mills, middlings-purifiers, and various other machines in which the material is to be fed in wide thin streams, a hopper is used, generally provided with a feed-roller at its bottom, and having an adjustable valve arranged at a distance from the periphery of the roller, determined by the amount of feed required.

My invention relates in part to the construction of said valve and to the devices whereby it is adjusted, and in part to mechanism whereby an agitation of the material in the hopper is obtained analogous to that given the shoe by the damsel in the old burr-mills, and in carrying it out said valve is suspended within the hopper and made vertically adjustable by means of screw-bolts set in overhead supports. This vertically-adjustable valve is formed with a hinged lower section spring-pressed toward the periphery of the feed-roller, but restrained at any given distance therefrom. The suspended valve and the screws by which it is vertically adjusted are combined with a tension bolt or bolts passing through the side of the hopper and ball-jointed to the valve, whereby the latter may be adjusted in and out toward or from the feed-roller to bring the lower edge of the inner section nearer to or farther from its periphery. The feed-roller is provided with eccentric journals, whereby the material in the hopper is agitated by the irregular movement of the periphery. The eccentrically-journalled feed-roller is combined with a hinged flap or cut-off valve at the rear of the hopper to bar the escape of the material, and a hinged feed-valve at the front. The hinged feed-valve has feet, which rest against the periphery of the eccentrically-journalled feed-roller, or are struck thereby as the longer radius of the roller comes around, whereby the feed-valve is pressed away from the roller and the feed-

passage kept open, and various other combinations and details of construction are employed either as principals or accessories, all as hereinafter described and claimed.

For the purpose of explaining my invention, it will be sufficient to illustrate and describe it in connection with a set of rolls such as employed in the roller-mills of the present date; but, as already stated, I do not intend thereby to limit myself to its use upon this class of machines alone.

In the drawings, Figure 1 is a side elevation, in section, of a feed-hopper embodying so much of my invention as relates to the adjustment of the valve, provided with an ordinary feed-roller, and arranged in proper position over a set of comminuting-rolls. Fig. 2 is a front elevation thereof, partly broken away to expose certain of the operative devices. Fig. 3 is a like side elevation of a hopper embodying my invention, including eccentric feed-roller and the hinged rear valve; and Fig. 4 is a front elevation thereof.

A represents the hopper, which is placed directly over each set of rolls to be fed in the usual manner, and B, in the first two figures, any ordinary feed-roller at the base of said hopper. At the top of the hopper, almost above the feed-roller, but somewhat obliquely therefrom on the discharge-side, is placed a bridge strap or support, C, which receives adjusting-screws D, shouldered to rest upon the strap, but at their lower ends screw-threaded to take into eyes d projecting from the inner side of a suspended valve, E, that extends from end to end of the hopper parallel with the wall thereof and fits snugly against the end boards, yet so as not to have appreciable frictional contact therewith. Tension-bolts F pass through threaded eyes in the front side of the hopper, which permit a limited swiveling action, and are ball-socketed in or have a tumbling connection with the valve, so that while the latter receives its vertical adjustments from the set-screws in the bridge-strap it may receive in-and-out adjustments toward or from the periphery of the feed-roller by means of the tension-bolts. At a point beneath the tension-bolts the valve is divided longitudinally and receives a lower

section, jointed thereto by spring-hinges *f*, which tend to press it constantly into line with the upper section until checked by the meeting of the adjacent planed edges of the 5 two, and also under certain circumstances, as when, owing to the roller being longitudinally grooved or fluted, this is desirable, to press it against the periphery of said roller; but whether resting upon the periphery or away 10 from said hinges permit it to yield when a lump or other mass of more than average size is carried against it.

I have found that by giving the screw-eyes by which the valve is suspended a length of, 15 say, about five inches in a hopper of the ordinary size, a sufficient equilibrium can be reached to retain any amount of feed, provided said eyes are made adjustable, so that their length may be reduced from or increased 20 to the limit named. Such adjustment may be secured by means of clamping-nuts *g*, applied to the threaded shanks of the screw-eyes, and it acts on the same principle as moving the sliding weight on a scale-beam. This in 25 many cases enables me to dispense with the tension-bolts, although they may be retained as auxiliary to such construction.

The material in the hopper will feed better if constantly agitated, and for this purpose 30 beaters or stirrers have been heretofore placed upon a driven shaft running parallel with the feed-roll and immediately above it. The action of this, however, is to grind and tumble all the particles of material or middlings and 35 against each other, unnecessarily abrading them and producing an abnormal quantity of dust. A feed-roll has also been employed having endwise reciprocations imparted to it, which is said to slightly agitate the material, 40 and thus lighten it sufficiently for the purpose; but to obtain a more perfect agitation than afforded by the latter device, while avoiding the undue abrasion caused by the former, I have devised the eccentric feed-roll *H*, (shown 45 in the last two figures of the drawings.) This may be turned true and round, as indicated, with eccentric-journals *h*, or it may be oblong in cross-section, giving the effect of a double eccentric or acting twice in one revolution, the 50 journals being placed at the intersection of the two diameters.

The hopper and feed-valve employed may be of the same general construction, and the same adjusting devices used as just described; 55 but the rear of the hopper will have a hinged flap or valve, *K*, pressed elastically by means of a spring, *k*, against the periphery of the roller, so as to cut off the escape of material on that side. This flap or cut-off valve is 60 shown as pressing upon the side of the roller about opposite its horizontal diameter, but it is obvious that it may rest upon the top at a short distance from the feed-valve, so as to be lifted against the mass of material in the hop- 65 per as the longer diameter of the roller or eccentric comes around. Instead, however, of the specific feed-valve heretofore described,

some other construction may be employed, provided that the valve or the lower section thereof is hinged and pressed toward the periphery of the roll as required by the action thereof. If 70 the roll has longitudinal feed-grooves, the edge of the valve may rest upon its periphery along the whole length; but as it is usually desired to have a slight aperture between the two to allow the material to be fed in a 75 long thin sheet, and as the valve will be set to such adjustment in reference to the shorter axis of the roll, I propose to supply it at its ends with feet *k'*, projecting sufficiently to 80 touch the periphery at such point, since otherwise the feed of the material may not force the valve back quickly enough when the long axis comes around. These feet may be and it will probably be found advisable to 85 make them adjustable. They will constantly press against the periphery, and will cause the roller in its revolutions to keep the valve positively at the precise distance required. Instead, also, of employing the screw-threaded 90 tension-bolts heretofore proposed, other bolts may be substituted for them, as shown in said latter figures, fixed or hinged to the side of the hopper or to some other stationary support and ball-socketed to the valve, and having a nut, *L*, upon their screw-threaded thimbles between said side and the valve, whereby a coiled spring, *l*, encircling the spindle between the nut and the valve may be adjusted in stress to cause the lower edge of the valve 95 to press more or less forcibly against the roll.

I claim—

1. The combination, substantially as hereinbefore set forth, with a feed-hopper, of a valve suspended therein, a bridge or support 105 across the top of the hopper, and screws passing therethrough and taking into eyes on the valve, whereby the latter is adjusted vertically.

2. The combination, substantially as hereinbefore set forth, with a feed-hopper, of a valve suspended therein, screws set in overhead supports, whereby it is vertically adjustable, and screws passing through the side of the hopper to a universal connection with the valve, whereby it is adjustable in and out to 115 ward and from the feed-roll.

3. The combination, substantially as hereinbefore set forth, in a feed-hopper, of a feed-roll, a vertically-adjustable valve, a lower section hinged to said valve, and springs which 120 tend to close said lower section toward the feed-roll.

4. The combination, substantially as hereinbefore set forth, in a feed-hopper, of a feed-roll, a vertically-adjustable valve, a lower section hinged to said valve, springs pressing 125 said lower section toward the feed-roll, and tension-bolts passing through lateral supports and acting against the main section to adjust it toward the feed-roll.

5. The combination, substantially as hereinbefore set forth, of a feed-hopper, a valve therein, overhead supports for said valve, adjustable screws suspending the valve from 130

said overhead supports, tension-bolts passing through the sides of the hopper and acting upon the valve to adjust it toward and from the feed-roll, and a hinged lower section to the valve, adjacent to the feed-roll, which is pressed toward said roll by springs.

6. In combination with a feed-hopper, an eccentric feed-roll placed at the discharge-point thereof, substantially as hereinbefore set forth.

7. The combination, substantially as hereinbefore set forth, in a feed-hopper, of an eccentric feed-roll placed along the bottom thereof, a cut-off valve at the rear of the hopper pressing against the feed-roll to prevent the escape of material at that point, and a hinged feed-valve at the front of the hopper.

8. The combination, substantially as hereinbefore set forth, in a feed-hopper, of an eccentric feed-roll, a hinged cut-off valve along the rear of the hopper spring-pressed against the feed-roll to prevent the escape of material at that point, a hinged feed-valve at the front of the feed-roll spring-pressed toward said feed-roll, and adjusting devices to move said valve toward or from the roll while permitting it to yield from any given adjustment.

9. The combination, substantially as hereinbefore set forth, in a feed-hopper, of the eccentric feed-roll, the hinged valve pressing against it at the rear to prevent the escape of material at that point, the vertically-adjustable feed-valve, and the hinged section along the foot of said valve spring-pressed toward the feed-roll.

10. The combination, substantially as hereinbefore set forth, in a feed-hopper, of the eccentric feed-roll, the cut-off valve pressing against it at the rear to prevent the escape of

material at that point, the vertically-adjustable feed-valve, the tension-bolts whereby said valve is moved in and out, and the hinged section along the foot of said valve spring-pressed toward the feed-roll.

11. The combination, substantially as hereinbefore set forth, in a feed-hopper, of the eccentric feed-roll, the cut-off valve closing the escape of material at the rear of said roll, the hinged feed-valve spring-pressed toward the feed-roll, and the feet from said feed-valve pressing against the periphery of the roll.

12. The combination, substantially as hereinbefore set forth, with a feed-hopper and feed-roller, of a feed-valve suspended from overhead by means of eyes which project from its inner side near the top, whereby the foot tends to swing inward against the feed-roll to establish equilibrium.

13. The combination, substantially as hereinbefore set forth, with a feed-hopper, of a feed-valve suspended from overhead by means of supports which project from its inner side near the top, and means whereby said supports may be adjusted in length to shift the center of gravity of the valve.

14. The combination, substantially as hereinbefore set forth, with a feed-hopper, of a feed-valve suspended from overhead by means of supports which project from its inner side near the top, means whereby the supporting-point may be shifted toward or from the body of the valve to change the center of gravity, and means whereby said valve may be raised and lowered.
